UNITED STATES PATENT OFFICE.

WILLIAM CHURCH TAYLOR, OF BUFFALO, NEW YORK.

FORM FOR MACHINE BOOKKEEPING.

Application filed February 8, 1919. Serial No. 275,709.

To all whom it may concern:

Be it known that I, WILLIAM CHURCH TAYLOR, a citizen of the United States of America, residing in the city of Buffalo, county of Erie, State of New York, have invented certain new and useful Improvements in Forms for Machine Bookkeeping, of which the following is a full, clear, and exact description.

10 My invention relates generally to record and account forms, and more particularly to combined daily and weekly balance forms for use in banks.

15 The principal object of my invention has been to provide a form by which the daily as well as the weekly balances shall be conveniently posted at the bottom of each sheet, whereby the ledger may be proved and the accounts easily and quickly analyzed by 20 making it possible to have all daily balances on separate sheets clearly in view and under one another at one time.

25 Another object has been to provide a form having vertically arranged spaces by which it shall be easy to pick out interest balances and average balances of accounts, thereby obviating the errors resulting from forms having horizontal ruling.

30 Another object has been to provide a form having an arrangement of ruling and numbers at the top of the sheet so as to allow plenty of space for names without crowding and at the same time permit easy cross entries.

35 Another object has been to provide a bookkeeping form which shall provide a system capable of greater speed in manipulation than the present machine systems, and at the same time provide one much more efficient in 40 its operation and one more accurate in results.

45 Another object has been to provide a form so arranged that it may be placed upon one side of a single sheet and accommodate ten separate and individual accounts. If desired, the form may be repeated on the opposite side of the sheet, thus providing for twenty accounts. My form, therefore, provides a system which is very economical in 50 the amount of material used; saves time when in use, making it necessary to handle only one sheet for twenty accounts instead of twenty separate sheets as is customary in many present forms of machine bookkeeping; and, economizes in filing space.

55 Another object has been to dispense with

all elaborate rulings, thus providing a form which may be easily printed and cheaply produced.

Furthermore, machine bookkeeping by the use of my form is made very simple and exceedingly flexible in its use.

The above objects and advantages have been accomplished by the form shown in the accompanying drawings, which are a part of this application. In the drawings:

Fig. 1 shows a sheet designed for use in bookkeeping machines, having its ruling in accordance with my invention.

Fig. 2 is an enlarged view of the lower left-hand corner of the sheet.

The sheet is provided with a plurality of vertically arranged columns A, preferably ten in number, and formed by lines C and C'. Across the top of the sheet are provided 75 preferably three horizontal spaces H, H', and H². The lines C and C' are alternately arranged. The spaces H and H' are divided into name spaces B and B' by the extension of lines C. The spaces H² are divided into 80 column spaces b and b' by the extension of lines C and C'. At the left-hand side of each of the name spaces B is placed an even number, and at the right-hand side of each of the name spaces B' is placed an odd number. By reference to the drawing it will be seen that the first one of the name spaces B is numbered 0, and the next is numbered 2, and so on up to 8. The name spaces B', in like manner, are numbered 1, 3, and so on 85 up to and including 9. The spaces b and b' are also provided with numerals which correspond, respectively, with the numerals of the name spaces B and B'. By this arrangement, it will be seen that the numerals in 90 the spaces B and b, and the numerals in the spaces B' and b' are substantially beneath each other and thereby permit easy cross entry and greatly reduce the possibility of error.

Each of the sheets having my form 100 is given a folio numeral D, and this numeral is used in connection with the numerals in the name spaces B and B' in identifying the customer's account in the ledger; for instance, the customer's number in the space B opposite the numeral 0, on sheet 1, would be 10. Likewise the number of the customer whose name appears in space B' would be 11, and so on throughout sheet 1. On sheet 2, the customer's numbers would be 20, 21, 110 22, and so on. This makes it possible to prepare a list of checks for each account

separately on a journal, giving them a number to correspond with the number of the account or column on the sheet, and at the same time enable one to use my form as a 5 balance extension sheet. Heretofore, in machine bookkeeping, it has been customary to journalize the checks and then list them over again on the ledger page. This second listing is eliminated in my system as the check 10 amounts in journalizing are given the customer's number, found at the head of his column. This extension of the balance, in my system, is automatically accomplished on the machine, it being necessary, only, to 15 put down the old balance and then, for instance, the total debits (taken from the journal). The machine subtracts these amounts and gives, at once, a new balance, thus saving a great deal of time over the pen and 20 ink methods of other systems.

At the bottom of the sheet is provided six horizontal spaces E and one horizontal space F. The spaces E are divided into spaces e by the lines C and C', forming the vertical 25 columns A, and these spaces are, therefore, of lengths equal to the widths of the vertical columns. At the extreme left-hand side of the sheet is provided a narrow column G, divided at its lower end, into six spaces by 30 the lines forming the spaces E, and having one day of the week printed in each space. The date may also be placed in these spaces. The space F is divided at its right-hand side into six spaces f by the lines C and C', 35 which are at the right-hand side of the sheet. At the left-hand side of this space F is preferably printed the words "Total balances".

At the top of each of the vertical columns 40 A is preferably printed the word "Balance"; and, when the sheet is to be used, the customer's balance is placed at the top of the column bearing the number which corresponds to the number opposite his name in 45 the space B or B'. During the course of the day one or more debit or credit entries are made in the column beneath the balance, both the debit and credit items for each individual account being placed directly beneath 50 one another in the same vertical column. Various means of identifying the different items may be employed, the debit items being 55 preferably designated by a minus sign, the credit items by the term "Dep" or a plus sign, and the balances by the term "Bal" or an asterisk. As shown in the drawing, the column numbered "0" shows an account started with a balance of \$5,000.00 and four debits of \$500.00 each, each debit being so 60 indicated by means of a minus sign, and one credit or deposit of \$1,000.00 designated by the term "Dep". The balance at the end of this first day (for convenience called Monday) is \$4,000.00, and this balance is preferably repeated in the column to show the bal- 65

ance for the beginning of the following day. At the end of the day, or the morning following, the balance in addition to being extended in the column, is placed in the space e below the column opposite the day of the week on which the balance is struck similarly, the second day (e. g., Tuesday), starting with a balance of \$4,000.00, carried forward from the preceding day, the account shown in the drawing indicates four debits of \$100.00 each, the balance for that day being \$3,600.00, which amount is entered at the bottom of the column in the space e for Tuesday's balance. If desired, amounts of checks may be entered individually in the column or may be blocked before being entered. The block method is indicated by the entries in column numbered "1" in the drawing, the entry "4550.00—" representing the aggregate amount of debits for that day. At the end of the next business day the balance for that day is placed in the next space e below the column, and so on throughout the week. The daily balances for the customers of any one sheet for each day are then 70 added and placed in the spaces f. Thus, in the first space f would be the total balance for Monday; in the second space f would be placed the balance for Tuesday, and so on throughout the week, each total daily balance being placed in the next successive space f.

As a result of this balance feature of my form, many advantages are derived. The daily balances act as a reference or guide 100 to the transactions of any particular day. If, for instance, it is desired to find the record of any check, it is necessary, only, to refer to the daily balance in the space e opposite the date of the check and then refer 105 to that particular balance in column A above where the check will be found specifically entered or blocked above that balance. Thus the use of all dates in column A is obviated. The date opposite spaces e 110 and the daily balances are sufficient identification when tracing any particular transaction.

When the sheets are bound in the ledger they may be shifted so that the balances at the bottom of a number of consecutive sheets may be conveniently brought into view at the same time, thus making a convenient daily balance ledger. All the balances are thus arranged in a vertical column, which 115 makes the account easy to analyze.

It is very easy to pick out an interest balance in my form, because all the balances are arranged in a vertical column. All the 120 chances for errors in forms where the balances are arranged in horizontal columns at some distance from each other, are eliminated.

With my form, it is much easier to get an 125 accurate average balance, because the bal-

ances are arranged in the same vertical column and can be easily footed, while in the other systems this is difficult as the balances are arranged horizontally in different columns. Where the balances are all arranged vertically in the same column and directly beneath one another, it is very easy to note a fluctuation in any one of the accounts.

These balances are also of use in providing the ledger. After a daily balance for each account is placed in the space provided, the total balance for each day's accounts on each of the sheets is placed in the proper total-balance spaces, and these amounts are then recapitulated and used directly in providing the ledger, instead of making it necessary to list the balances on a separate sheet before recapitulation.

Obviously, my form may be designed to accommodate only three days' work instead of six days' work. This, as well as other detailed modifications of the form herein shown and described, may be made without departing from the spirit of my invention or the scope of the appended claims; and, I do not, therefore, wish to be limited to the exact embodiment herein shown and described.

Having thus described my invention, what I claim is:

- 30 1. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being appropriately designated for use as daily balance spaces.
- 40 2. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces, each of the wider of said transverse spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being appropriately designated for use as daily balance spaces.
- 50 3. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being appropriately designated for use as daily balance spaces.
- 60 4. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being appropriately designated for use as daily balance spaces.

ing across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, one of the name spaces and one of the column spaces being similarly designated, and the other name and column spaces being similarly designated.

3. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being appropriately designated for use as daily balance spaces.

4. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being appropriately designated for use as daily balance spaces.

- spaces being designed to receive a name, one of the name spaces and one of the column spaces being similarly designated, and the other name and column spaces being similarly designated, a plurality of spaced horizontal lines across the form near the bottom margin thereof, forming a plurality of transverse spaces beneath each vertical column space and of equal width thereto, said transverse spaces being adapted to be used as daily balance spaces, and a plurality of date spaces near the side margin of the form, one for each horizontal row of transverse spaces, said date spaces containing matter forming an appropriate designation of the transverse spaces for use as daily balance spaces.
5. A form for machine bookkeeping having a plurality of spaced vertical lines forming a plurality of vertical columns, each appropriately designated for use as an account column and each adapted to be used as a combined debit and credit individual account column, a plurality of spaced horizontal lines across the form near the top margin thereof forming transverse spaces, alternate ones of said vertical lines extending across the lowest of said transverse
- 10

spaces only and the others of said vertical lines extending substantially to the top margin of the form, to form a pair of transverse column spaces each equal in width to one of the first-mentioned vertical column spaces and a pair of transverse spaces each equal in width to the corresponding number of said column spaces, each of the wider of said transverse spaces being designed to receive a name, a symbol in each column space and a symbol in each name space corresponding to the symbol in the column space beneath it, the column symbols and the name space symbols being placed near each other to facilitate identification, a plurality of spaced horizontal lines across the form near the bottom margin thereof, forming a plurality of transverse spaces beneath each vertical column space and of equal width thereto, said transverse spaces being appropriately designated for use as daily balance spaces, the lowermost row of transverse spaces being appropriately designated for use as total daily balance spaces.

In testimony whereof, I have hereunto signed my name.

WILLIAM CHURCH TAYLOR.
